UNITED STATES PATENT OFFICE.

EDWARD EWART, OF MOOSUP, CONNECTICUT.

SHEDDING MECHANISM FOR LOOM-HARNESS.

1,333,164.

Specification of Letters Patent.

Patented Mar. 9, 1920.

Application filed September 23, 1918. Serial No. 255,336.

To all whom it may concern:

Be it known that I, EDWARD EWART, a citizen of the United States, residing at Moosup, in the county of Windham and State of Connecticut, have invented certain new and useful Improvements in Shedding Mechanism for Loom-Harness, of which the following is a specification, reference being had to the accompanying drawings.

10 This invention relates to an improved shedding mechanism for loom harnesses, and has for its primary object to provide simple and easily operable means for opening and closing the harness shed.

15 It is a more particular object of the invention to provide a device for the above purpose embodying a plurality of jacks arranged above and below the harness and operatively connected thereto, and a single control lever connected to the two series of jacks for simultaneously actuating the same to raise or lower the harness.

20 And it is a further general object of my invention to provide a mechanism for operating loom harnesses which consists of relatively few parts not liable to get out of order, and which can be manufactured at comparatively small cost and readily applied to the ordinary loom.

25 With the above and other objects in view, the invention consists in the improved construction, combination and relative arrangement of the several parts as will be herein-after more fully described, subsequently 30 claimed and illustrated in the accompanying drawings in which similar reference characters designate corresponding parts throughout the several views, and wherein:—

35 Figure 1 is a side elevation, partly diagrammatic, illustrating the preferred embodiment of the harness operating mechanism and showing the harness in its lowered position;

40 Fig. 2 is a similar view illustrating the relative positions of the jacks and the control lever when the harness has been raised to open the shed;

45 Figs. 3 and 4 are detail perspective views of one pair of the jack members connected to the harness;

50 Fig. 5 is a similar view of the jack for actuating the lower pair of harness jacks; and

55 Fig. 6 is a perspective view of the control lever.

Referring in detail to the drawings, 5

designates the loom harness, which may be of any approved construction and mounted in its operative position upon the loom in any conventional manner.

60

6 and 7 respectively indicate upper and lower jack members of similar form, each of said members having two arms disposed at obtuse angles relative to each other. These members at the juncture of their arms are 65 pivotally mounted, as at 8 and 9 respectively.

The jacks 6 and 7 are arranged adjacent to one end of the loom harness, while at the other end thereof, a second pair of jacks, designated 10 and 11 respectively, are arranged above and below the harness. Each of the latter jacks has three arms which radiate from a common center or hub, at which point the jacks are pivotally mounted or supported, as shown at 12 and 13 respectively.

70

In spaced relation to the lower jacks 7 and 11, an additional jack 14 is pivotally mounted, as at 15, said latter jack being in the form of a bell crank lever having its arms 80

extending at right angles from the pivot. The arms of each jack above referred to at their outer ends are relatively wide and have rounded end edges, indicated at 16, which merge into one longitudinal side edge of the 85 arm. In the other longitudinal edge of the jack arm, a notch or recess 17 is formed to receive a flat link or stirrup 18. The rounded end edges of the jack arms serve to prevent the link or stirrup from accidentally 90 jarring off of the end of the arm.

To the upper and lower edges of the harness frame, in spaced relation to each end thereof, the usual hooks 19 are secured. Jack rods 20 have loops formed on one of 95

their ends for engagement in the hooks 19, while the other ends of said jack rods are engaged with one of the stirrups 18 of each of the jack members 6, 7, 10 and 11 respectively. The other arm of each jack member 100 6 and 7 is connected to another of the arms of the respective jacks 10 and 11 by the rods 21, the ends of which are suitably engaged with the stirrup members 18. The remaining arm of the lower jack member 11 is connected by the rod 22 to one arm of the jack member 14.

105 23 designates the control lever which is formed with a pair of arms extending at an obtuse angle relative to each other, said control lever being pivotally mounted at the juncture of said arms, as at 24. Each of

said lever arms is provided in one of its edges with a series of spaced notches 25, in one of which a strap link or stirrup 26 is adapted to be engaged. The stirrup on one lever arm 23 is connected by the rod 27 to the remaining arm of the upper jack member 10, while the other lever arm 23 is similarly connected by the rod 28 to the other arm of the jack member 14.

10 In the lowered position of the loom harness, one arm of the control lever 23 is disposed in a horizontal position from the pivot 24, while the other arm extends upwardly at an oblique angle with relation thereto. In 15 order to raise the loom harness to open the shed, the lever 23 is actuated, the horizontal arm moving downwardly, and the other arm to a substantially vertical position. In this movement of the control lever, the arms of 20 the jacks swing in arcuate paths and through the medium of the connections 27 and 21 between the control lever and the upper jacks 6 and 10, the arms of said jacks which are connected to the harness frame swing upwardly. The jack 14 being simultaneously 25 actuated through the medium of the rod 28 connected to the control lever, and said jack member being in turn operatively connected to the jacks 7 and 11 by the rods 21 and 22, 30 said latter jacks are also actuated and the arms thereof which are connected to the harness frame, are also caused to move upwardly. Thus, there will be no resistance to the upward movement of the harness. This 35 opening of the harness shed necessitates a vertical movement of the harness of only about four inches, and by means of my improved arrangement of the jack members and their connections with the control lever, 40 this movement may be easily and quickly effected. As will be readily understood the harness may be positively returned to its lowered position to close the shed by simply reversing the movement of the lever 23.

45 From the foregoing description, taken in connection with the accompanying drawings, it is believed that the construction, manner of operation and several advantages of the invention will be clearly and fully understood. My improved harness operating mechanism is very simple in its construction and, therefore, not liable to get out of order, but will be positive and reliable in practical operation. Also, the construction and relative arrangement of the several jack members is such as to enable the device to be readily applied to use upon the ordinary

loom without necessitating any modifications in the construction thereof or in the mounting and arrangement of the loom harness. 60 While I have herein specifically described the preferred operating connection between the several jack members and between the jack members and the loom harness, it is apparent that the invention is not limited in its 65 utility to such structural details. The device is likewise susceptible of many modifications in the form, construction and arrangement of the several jack members and the control lever, and it is accordingly to be understood that I also reserve the privilege of adopting all such legitimate changes as may be fairly embodied within the spirit and scope 70 of the invention as claimed.

I claim:—

In combination with a loom harness, a pair of jacks rotatably mounted above the harness, one of the jacks having two angularly disposed arms and the other jack having three angularly disposed arms, operative 80 connections between one of the pairs of the three-arm jack and one of the arms of the two-arm jack, a pair of jacks disposed below the harness, one of the jacks having two angularly disposed arms and the other having three angularly disposed arms, the jacks having two arms being disposed in vertical alignment with each other, an operative connection between one of the arms of the lower three-arm jack and one of the arms of the 90 lower two-arm jack, operative connections between one of the arms of each three-arm jack and the corresponding end of the loom harness, operative connections between one of the arms of each two-arm jack and the 95 corresponding end of the loom harness, an additional jack having angularly disposed arms, one arm of the latter jack being connected to one arm of the lower three-arm jack, a pivotally mounted control lever having angular disposed arms, an operative connection between one of the lever arms, and an arm on the last named jack and between the other of the arms of the control lever and one arm of the three-arm upper jack, 100 whereby all of the jacks are simultaneously actuated by the oscillation of the lever to alternately raise and lower the harness.

In testimony whereof I hereunto affix my signature in the presence of two witnesses.

EDWARD EWART.
